UNITED STATES PATENT OFFICE.

FRED MEARS, OF MINNEAPOLIS, AND JOSEPH CRAIG, OF PRINCETON, MINNESOTA, ASSIGNEES, BY DIRECT AND MESNE ASSIGNMENTS, TO HYGIENIC REFINER COMPANY, OF PRINCETON, MINNESOTA, A CORPORATION OF MINNESOTA.

APPARATUS FOR BLEACHING AND AGING FLOUR AND OTHER GRAIN PRODUCTS.

No. 882,526.

Specification of Letters Patent. Patented March 17, 1908.

Application filed April 27, 1907. Serial No. 370,719.

To all whom it may concern:

Be it known that we, FRED MEARS and JOSEPH CRAIG, citizens of the United States, residing at Minneapolis and Princeton, in the 5 counties of Hennepin and Millelacs and State of Minnesota, have invented certain new and useful Improvements in Apparatus for Bleaching and Aging Flour and other Grain Products; and we do hereby declare the following to be a full, clear, and exact description of the invention, such as will enable others skilled in the art to which it appertains to make and use the same.

Our invention has for its object to provide 15 an efficient apparatus for bleaching and aging flour and other grain products; and, to this end, our invention consists of the novel devices and combinations of devices herein-after described and pointed out in the claims. 20 The apparatus is illustrated in the accompanying drawings, wherein like notations indicate like parts throughout the several views.

Referring to the drawings; Figure 1 is a 25 view chiefly in side elevation, but partly in vertical section, with some portions broken away, illustrating our improved apparatus. Fig. 2 is a plan view of the parts shown in Fig. 1, with some portions removed and others shown in diagram lines only. Fig. 3 is a 30 detail showing the flour distributing head detached, in plan view; and Fig. 4 is a detail showing the gas generator detached, chiefly in vertical section but with some parts in 35 elevation.

Upon a suitable skeleton frame 1 is mounted a pair of cylindrical mixing vessels 2, closed at their upper ends and having hopper-like bottoms. In each of these vessels 2 is suitably supported a rotary shaft 3, having at its upper end a beveled pinion 4 engaging a bevel gear 5 on countershaft 6. Each countershaft 6 is shown as provided with a sprocket wheel 7 connected by a chain 45 8 with a main shaft 9 receiving motion from any suitable source, not shown.

As shown, the shaft 3 is supported by a bearing bracket 10 fixed to the walls of the mixing vessel 2, and an upper bracket 11 50 projecting from a standard 12 rising from the main frame 1, and which also supports the bearings for the shaft 6. To the lower end of the shaft 3 is fixed a screw blade 13 coöoperating with the shaft 3 to afford a

screw conveyer working in the neck or outlet 55 of the hopper-like bottom of the mixing vessel 2. To the shaft 3, within the vessel 2, at a suitable point below the head or upper end of the vessel 2, is located a flour distributing head 14 which, as shown, is of approximately 60 disk-like form, its central portion being a solid web and its outer portion being made up of radial projections or fingers extending outward from the solid web, and bent upon themselves so as to assume somewhat the 65 shape of propeller blades or paddle arms, as can be readily understood from an inspection of Figs. 1 and 3. The flour is supplied from an overhead source through the main trunk or chute 15, having a pair of diverging 70 legs 16, the feet sections of which are vertical and of cylindrical form, and tap or are secured to the heads of the vessels 2. At the point where the legs 16 diverge from the trunk 15, is located a weighted valve 17 75 which may be shifted to throw the flour to either of the vessels 2 and shut the same off from the other, whenever so desired. In the vertical or feet sections of the legs 16 is mounted a flanged sleeve 18 in such a way 80 that it will telescope or move freely up and down therein. The sleeve 18 is adjustably supported by a hand screw 19 tapped through the head of the vessel 2 and taking hold of the sleeve flange. The shaft 3 passes 85 out through the sleeve 18 and the vertical section of the flour supply leg 16. By adjusting the sleeve 18 up or down, it may be brought nearer to or farther away from the distributing head 14, and thus be made to 90 regulate the flour or feed supply to the mixing chamber 2.

On the top of the frame 1 is mounted a suitable casing 20 adapted to support the working parts of the gas generator. As 95 shown, the casing 20 is provided with a door 20^a, and a false bottom 21 mounted on hand screw 22 and adapted to be raised or lowered thereby within the casing 20. On the false bottom 21 is removably mounted the retort 100 or generating vessel 23 composed of refractory material, such as glass or porcelain. Above the generating vessel 23 is a collector 24, shown as removably supported on shelves 24^a. The collector 24 has a hopper-like 105 bottom adapted to fit within the neck of the generating receptacle 23 and form a tight joint therewith, when the latter is raised to

its highest position by the hand screw 22. The collector 24 is preferably made of aluminium, but may be made of other suitable material which will not be attacked by the generated gas. From one end of the collector 24 extends a main delivery pipe 25 which splits into two branches 26 tapping the respective mixing vessels 2 through the top walls of the same, as clearly shown in Fig. 1 of the drawings. At the junction of the branches 26 with the main pipe 25 is located a weighted valve 27 for directing the gas into either of the vessels 2 and cutting the same off from the other, whenever so desired. An aluminium tube 28 is adjustably suspended within the generator. As shown, the tube 28 is suspended from the top wall of the collector 24 by means of nuts 29 having screw threaded engagement with the upper or screw threaded portion of the tube 28. The tube 28 is closed at its opposite ends but is perforated in the part thereof which works within the generating vessel 23 and the collector 24. The tube 28 is adapted to support a generating rod 30 of galvanized iron, in such a way that the rod will automatically feed down, by gravity, as the lower end of the rod is consumed in the gas generating action. In the receptacle 23 is placed a solution composed of two-thirds parts nitric acid and one-third part water. Into this solution is placed sulfate of copper to the amount of about three per cent. of the liquid solution. Then, when the rod 30 of galvanized iron is submerged in this solution, at its lower end, the generating action will take place; and the gas will accumulate in the collector 24 and will pass out therefrom through the pipes 25 and 26 into the mixing chambers 2, or one thereof, according to the way in which the valve 27 is set. The compounds of nitrogen and oxygen produced from the materials indicated, are heavier than the air, and hence, the gas will feed by gravity from the pipes 25 and 26 into the mixing chambers 2 and pass down through the latter. The gas supply pipe 26, to the respective mixing chambers 2, tap the heads of these chambers, at a point above the flour distributing head 14. Under the rotary motion of the distributer 14, the flour falling thereon, through the sleeve 18, will be thrown off from the distributer in the form of a shower, or in a finely divided condition, well adapting the gas, entering through the pipe 26, to get directly at all the different particles of the flour. The gas generated from the ingredients above noted is nitric oxide (NO); and, in view of the way in which the generator gets its delivery to the mixing vessels 2, the gas can be delivered into the said mixing chambers in its substantially generated form, *i. e.* nitric oxide. The flour supply chute sections 15 and 16 are always loaded full of flour, and the outlet 65 from the hopper bottom, under the action of

the screw propeller 13, will be loaded full of flour, the feed being adjusted properly to secure this result. It follows that the flour will enter the mixing chambers 2 and pass therethrough with very little (if any) air entering therewith. Hence, it will further follow that the gas will remain and be applied to the flour in the form of nitric oxide or as it was generated at the generator.

Tests and analyses, made by an expert chemist, have demonstrated that the nitric oxide is a most efficient form of bleaching agent. It is found that, with an apparatus such as herein disclosed, adapted to utilize nitric oxide as the chief bleaching agent, the bleaching takes place in much less time, or put another way, with much less gas per unit of flour than can be otherwise secured. The collector 24 is, however, provided at a point most remote from its outlet or delivery pipe 25, with a butterfly valve 31 which, if desired, can be set in its open position and thereby allowed to admit air to the collector 24, under the suction or outward movement of the generated gas into the delivery pipe 25. If sufficient air is thus admitted through the valve 31 into the collecting chamber 24 of the generator, the nitric oxide will take on an additional atom of oxygen and become peroxid of nitrogen (NO₂). The bleaching qualities of peroxid of nitrogen are well known. Our apparatus, however, is designed primarily to supply and do the work with nitric oxide, although capable of affording the necessary air to get peroxid of nitrogen, if that should be desired. So far as we know, we are the first to provide any apparatus capable of generating and applying nitric oxide to flour or other grain products, for bleaching and aging purposes. All bleaching and aging apparatus disclosed in the prior art, so far as known to us, delivers to the flour peroxid of nitrogen or peroxid of nitrogen commingled with more or less peroxid of hydrogen, or ozone with peroxid of hydrogen. None of these prior uses are similar to ours. We are the first, so far as we know, to treat flour, or other grain products, with nitric oxide. It should be noted that the flour and the gas are both supplied to the mixing vessels solely under the action of gravity, and that the mixing vessels are substantially air tight. It will, of course, be understood that the structure of the apparatus may vary to a considerable extent, without departing from the spirit of our invention.

While especially designed for bleaching and aging flour, it must be understood that the invention is applicable to bleach and age other grain products, when in a finely divided or comminuted condition, and, in the claims, the word "flour" is used in its broad or generic sense to cover any and all kinds of grain products in a finely divided condition.

The novel process of bleaching flour and other grain products, which consists in sub-

jecting the flour to nitric oxide gas (NO) herein disclosed, is not herein claimed, but is disclosed and claimed in another application filed as a division of this case.

5 The gas generator herein disclosed contains novel features constituting patentable invention not herein claimed, but which is claimed in a divisional application filed of even date with this amendment.

10 What we claim is:—

1. The combination of a nitric oxide generator and an inclosed flour and gas mixer admitting only the gas and flour.

15 2. The combination of a nitric oxide generator and an inclosed flour and gas mixer, receiving the gas by gravity, and having a feed

entrance and exit adapted, when in use, to become packed with flour.

3. The combination of a nitric oxide generator, an inclosed mixing chamber receiving the 20 gas by gravity, and having feed entrance and exit adapted, when in use, to become packed with flour, and a distributer for scattering the flour through the gas chamber.

In testimony whereof we affix our signatures in presence of two witnesses.

FRED MEARS.
JOSEPH CRAIG.
